(57) **CLAIM**

The ornamental design for a wireless charger as shown and described.

DESCRIPTION

FIG. 1 is a perspective view of a wireless charger showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is a perspective view of the wireless charger shown in another configuration; and,

FIG. 10 is an enlarged view of the encircled portion of the wireless charger labeled 10 in FIG. 2.

The evenly dashed broken lines shown in the drawings depict portions of the wireless charger that form no part of the claimed design. The dash-dot-dash broken lines encir-

(Continued)

cling portions of the wireless charger illustrated in enlargements form no part of the claimed design.

1 Claim, 10 Drawing Sheets
